UNITED STATES PATENT OFFICE.

SHERMAN D. CLEGG, OF DAYTON, OHIO.

DESIGN FOR A COUNTER DISPLAY CASE.

Application filed November 17, 1924. Serial No. 11,394. Term of patent 14 years.

To all whom it may concern:

Be it known that I, SHERMAN D. CLEGG, a citizen of the United States, residing at Dayton, in the county of Montgomery and State of Ohio, have invented a new, original, and ornamental Design for a Counter Display Case, of which the following is a specification, reference being made to the accompanying drawing, forming part thereof.

The figure is a perspective view of a counter display case showing my new design.

I claim:

The ornamental design for a counter display case as shown.

SHERMAN D. CLEGG.
